I. A. OBST.
PNEUMATIC ACTION FOR MUSICAL INSTRUMENTS.
APPLICATION FILED SEPT. 10, 1914.

Patented Jan. 21, 1919.

UNITED STATES PATENT OFFICE.

JOSEPH A. OBST, OF PAWTUCKET, RHODE ISLAND.

PNEUMATIC ACTION FOR MUSICAL INSTRUMENTS.

1,292,362.

Specification of Letters Patent.

Patented Jan. 21, 1919.

Application filed September 16, 1814. Serial No. 861,141.

To all whom it may concern:

Be it known that I, JOSEPH A. OBST, a citizen of the United States, residing at Pawtucket, in the county of Providence and State 5 of Rhode Island, have invented a new and useful Improvement in Pneumatic Actions for Musical Instruments, of which the following, taken in connection with the accompanying drawings, is a specification:

10 The present invention relates to improvements in the construction and operation of pneumatic actions for musical instruments. The present construction particularly adapts itself to the employment of a single valve 15 control for the motor pneumatic, in contradistinction to the double valve control ordinarily employed, and embodying primary and secondary valves, but it is to be understood that while the invention is shown and 20 described as a single valve action, the principles of the same are equally applicable to the double valve action.

The object of my invention is to simplify the construction and lessen the cost of devices of this character, and in particular, to increase the responsiveness of such devices by improvements directed to the control of the bleed devices thereof. Other and further objects will appear from the following description taken in connection with the accompanying drawings, in which—

Figure 1 is a sectional view of a device embodying my invention.

Fig. 2 is a similar view showing the parts 35 in different positions.

Fig. 3 is a fragmentary sectional view showing the parts in the positions which they assume at one stage in the operation of the device, and

40 Fig. 4 is a cross section on the plane of the broken line 4—4, Fig. 1.

Like parts are indicated by like reference characters in the different figures.

The drawing illustrates a single motor 45 pneumatic 1, the movable leaf of which carries an arm 2 which is adapted to actuate the corresponding abstract, not shown, of a keyboard operated instrument in a manner well understood and common to instruments of this class. The stationary leaf of the pneumatic 1 is supported beneath a valve box 3, which has a channel 4, communicating by means of a tube 5 with a corresponding aperture in the tracker board of the instrument, 50 not shown.

Each valve box 3 has a vacuum chamber 6,

in constant communication, through a common passage 7, with an exhausting device, not shown, in the manner common to devices of this class. The vacuum chamber 6 of 60 each valve box communicates with the channel 4 of said box by means of a restricted passage 8, commonly known as a "bleed" passage for the purpose of exhausting the air from channel 4 into the vacuum chamber 65 6. Below the vacuum chamber 6 and separated therefrom by a flexible diaphragm 9, is a recess 10 with which the channel 4 communicates.

The box 3 is formed with a chamber 11, 70 which is in constant communication, by means of a channel 12 with the interior of the motor pneumatic 1. Said chamber 11 has a port 13 leading to the vacuum chamber 6, and a port 14 leading to the atmosphere. 75 A double faced valve 15 is contained within the chamber 11 and adapted to control the two ports 13 and 14 thereof. The valve 15 has a stem 16 extending through said port 13 and preferably carrying on its end a disk 80 17, preferably disposed somewhat above the upper surface of the diaphragm 9 in the normal collapsed position of the latter, as shown in Fig. 1.

The said valve 15, in the position shown in 85 Fig. 1, wherein it rests by gravity on the bottom of chamber 11, closes the port 13 between said chamber and the vacuum chamber 6, and leaves open the port 14, to establish communication between the interior of 90 the motor pneumatic 1 and the atmosphere. In the position of the valve shown in Fig. 2, wherein it is shown as elevated by an air pressure beneath the diaphragm 9, the valve 95 shuts off the motor pneumatic from the atmosphere, and connects it with the vacuum chamber 6.

My present invention relates to the bleed device by which the initial air pressure is sustained beneath the diaphragm 9, during 100 the elevation of the valve 15, and by which the air pressure beneath the diaphragm is quickly reduced at the proper time to permit the fall of the valve 15 after the motor pneumatic 1 has collapsed, and the chief 105 object of my invention is to render the apparatus more quickly responsive in its action.

The operation of my improved device is as follows:—The normal position of valve 110 15 is shown in Fig. 1, but when a perforation of the traveling note sheet registers

with the tracker-board aperture with which the tube 5 is connected, the resulting impulse of air through the channel 4 fills the chamber 10 and lifts the diaphragm 9, carrying it into contact with the material surrounding the opening 18, and by its continued movement to lift the valve 15 to close the port 14 and open the port 13, as shown in Fig. 2, with the result that the diaphragm will substantially close the end of the bleed passage 8 and restrict the flow of air through the bleed passage so the normal air pressure admitted to the recess 10 will be effective to raise the valve 15 into the position shown in Fig. 2. The interior of the motor pneumatic 1 is thereby cut off from the outer air and connected with the vacuum chamber 6, resulting in the collapse of the movable leaf of the motor pneumatic 20 and the operation of the corresponding abstract in the usual manner.

The closing of the bleed passage 8 is not complete as a slight leakage of air will occur around the opening 18, for the reason that the contact of the diaphragm 9 with the material surrounding the opening 18 is not sufficiently intimate to wholly prevent a slight leakage of air into the vacuum chamber 6. So long as the opening in the tracker-board is uncovered by the note sheet, this leakage is negligible, but when the opening in the tracker-board is closed, the air pressure in channel 4 and recess 10 becomes reduced sufficiently to allow the diaphragm 9 and valve 15 to drop, thereby instantly opening the full area of the bleed passage 8 to the vacuum chamber.

The responsiveness of the apparatus is greatly increased as the slackness of the diaphragm 9 substantially closes the bleed passage in advance of the lifting of the valve 15, restricting the bleeding effect to the slight leakage around the opening 18 due to the imperfect contact of the diaphragm 45 with the material around the opening 18, although the area 20, Fig. 4, is preferably slightly rounded in order to reduce the leakage to a minimum which, however, will be sufficient, due to the pull of the vacuum chamber 6, to slightly reduce the pressure in the recess 10, while the perforation in the tracker-board is closed. The closing of the perforation in the tracker-board will therefore be followed by the depression of the diaphragm and the consequent rapid equalization of the air pressure in the recess 10 and the vacuum chamber 6 due to the complete opening of the channels 4 and 8 which are

of sufficient size to cause the pressure in the recess 10 to be instantly reduced to that of the chamber 6, rendering the apparatus extremely responsive to the opening and closing of the perforations in the tracker-board by the note sheet. In other words, the bleed aperture in my improved device is variable. 65 The passages 4 and 8 are of sufficient area in cross section to effect an instantaneous change in the air pressure of recess 10, while the passages 4 and 8 are restricted by the initial upward movement of the diaphragm 70 so long as the aperture in the tracker-board is open. When the valve 15 is in its lowest position some space exists between the diaphragm 9 and the disk 17, and the initial elevation of the diaphragm 9 carries it into the 75 position shown in Fig. 3, closing the opening 18, before the valve 15 is raised. In the position shown in Fig. 3, the air pressure in the recess 10 is substantially the normal air pressure so long as the corresponding perforation is open, and air is supplied freely 80 through the flexible tube 5. When the perforation in the tracker-board is closed by the note sheet, the leakage from the opening 18 reduces the air pressure in the recess 10 sufficiently to allow the weight of the valve 15 and the normal air pressure upon its upper surface to peel the diaphragm from the surface 20, and fully open the passage to the 85 vacuum chamber. 90

I claim,

In a pneumatic action for musical instruments, a vacuum chamber, an air chamber, a flexible diaphragm separating said chambers, an air channel for supplying air to said air chamber, a bleed passage normally open between said air channel and said vacuum chamber and entering said vacuum chamber through a wall of the vacuum chamber opposed to said diaphragm and lying in its 95 path as said diaphragm is actuated by the difference in air pressure on its opposite sides, a valve having its stem in the path of said diaphragm with normally a space between the valve stem and the diaphragm, 100 whereby the movement of the valve as actuated by the diaphragm will occur subsequent to the covering of the bleed passage by the diaphragm, and the reverse movement of the valve will occur subsequent to the uncovering of the bleed passage. 110
